JUG OR THE LIKE

Brooks D. Fuerst, Sylvania, Ohio, assignor to Owens-Illinois Glass Company, Toledo, Ohio,
 a corporation of Ohio

Application June 8, 1949, Serial No. 3,120

Term of patent 14 years

(Cl. D58—8)

To all whom it may concern:

Be it known that I, Brooks D. Fuerst, a citizen of the United States, residing at Sylvania, in the county of Lucas and State of Ohio, have invented a new, original, and ornamental Design for a Jug or the Like, of which the following is a specification, reference being had to the accompanying drawings, forming a part thereof.

In the drawings:

Fig. 1 is a side elevational view of a jug or the like, showing my new design;

Fig. 2 is an end elevational view thereof; and
 Fig. 3 is a top plan view thereof.

I claim:

The ornamental design for a jug or the like, substantially as shown.

BROOKS D. FUERST.
